HAND METAL STAMPING TOOL

Celestine A. Royer, Champaign, Ill., assignor to
 R. H. Bishop Company, Champaign, Ill., a corporation of Illinois

Application June 20, 1947, Serial No. 756,033

3 Claims. (Cl. 164—121)

2

This invention relates to a hand metal stamping tool for stamping or punching sheet metal.

It particularly relates to a hand tool which can be carried by the workman working on sheet metal such as tin, for the forming of joints in the making of air ducts and other devices made from relatively light gauge sheet metal.

Hand as well as power operated presses are available for stamping or pressing light gauge sheet metal but such presses are bulky and, of necessity, are maintained in a shop such as a tinsmith shop and the like. The present practice for cutting out sheet metal for the making of joints in sheet metal fabricated products is to first lay out with a pencil, chalk or crayon the portion to be cut out of the sheet metal according to the type of joint desired, and then to use sheet metal shears for cutting out the metal. This is a time-consuming process. In addition, it tends to inaccuracies not only in the laying out on the sheet metal but also in following the lay-out lines during the shearing operation. There is known to me no hand tool on the market in which a joint can be cut out of a corner of sheet metal in one operation. It is therefore the principal object of my device to provide a hand operated tool which can be carried by the workman for stamping out or punching out the metal while the workman is on the job.

It is a further object of the invention to provide a tool having sufficient leverage that the hand stamping operation can be easily accomplished.

In the cross lever or scissors type of tool, care must be taken to avoid slippage of the material upon stamping, cutting or punching. It is an object of my invention to provide a toggle operated lever in connection with the jaws and dies, which holds the material securely in position during the stamping operation.

Other advantages and objects of my invention will become apparent by referring to the drawings in which

Figure 1 is a side view of the device showing the cross lever type of construction.

Figure 2 is an end view of the device looking toward the jaws of the tool.

Figure 3 is a detail of the lever mechanism for holding the metal in place during the stamping operation.

Figure 4 illustrates one type of stamping of sheet metal which is frequently required by tinsmiths.

Referring to the drawings, a pair of lever arms 1 and 2 are provided which are pivotally attached to each other by means of the bolt 3.

5 Hand grips 4 and 5 of the scissors type are provided. The jaw of the device is generally referred to by the numeral 6. To the hand lever arm 2 is attached a table or shelf extension of the jaw marked 7. A similar table or shelf extension 8 is provided attached to the handle 1. In the usual construction each lever arm and portion of the jaw is made in one piece. The entire tool 10 is preferably made out of a good grade of steel which is ordinarily used in the manufacture of similar devices, such as cold drawn steel, high tensile steel, and the like.

15 Detachable dies are attached to the jaws which include the jaw extensions. The upper die 9 is attached to the upper jaw by means of the bolts or screws 10. The lower die 11 is attached to the lower jaw by means of the bolts 12. Openings 13 in the dies engage the pins 14, 20 the pins 14 being permanently attached to the jaws, in order to fix the proper position of the dies on the jaws before attaching the various screws or bolts which hold the dies in place.

25 A separate toggle arranged hand lever is provided for holding the material securely in place during the stamping operation. Referring particularly to Figures 2 and 3, an L-shaped arm 15 is provided having a projection 16 which projection is properly shaped and sharpened for biting into the material and holding it in place. 30 The arm 15 is pivoted at 17 to the supporting members 18, supporting members 18 being attached by welding or other means to the table extension 8 of the lower jaw. The hand lever arm 19 is pivotally attached at the point 20 to the arm 15 and the pivot point 20 is spaced from but adjacent the end of arm 19 to which the toggle link 21 is pivotally attached at the point 22. The toggle link 21 is also pivotally attached at point 23 between the supports 18.

35 In the position shown in Figures 1 and 3, the hand lever is pulled back toward the hand grips 4 and 5 which forces the lever arm 15 downwardly toward the material, and the projection 16 in cooperating with the die 12 holds the material firmly in place. After the material is so held firmly in place the lever arms 1 and 2 are brought together and the metal is stamped out as indicated in Figure 4. By pushing the lever arm 19 away from the hand grips 4 and 5, the lever 15 is raised and the projection 16 is released from the material.

40 The handle 19, the toggle link 21 and the pivot points 20, 22 and 23 form a toggle arrangement for pivoting the arm 15 about the pivot 17. It is understood that any type of detachably

attached die or punch may be used in the device. The type shown is for stamping out what is commonly referred to among tinsmiths as a "Pittsburgh joint." The Pittsburgh joint which is stamped out by the dies is shown in Figure 4. The sheet metal is placed in the jaw 6 and the lever arm 19 operated so that the projection 16 holds the metal in place. The handles 1 and 2 are then brought together and the dies cut away portion A, outlined by the dotted lines on Figure 4, from the portion B, leaving steplike notches in the corner of the sheet metal.

One of the big advantages of my device is its flexibility that any type of die may be readily inserted in the hand tool and a separate hand tool does not have to be used for each kind of stamping operation. Also, the dies are readily removed for sharpening or replacement.

Other embodiments of my invention may be made within the following claims.

I claim as my invention:

1. A hand tool for blanking sheet metal comprising a pair of crossed hand levers pivotally attached to each other, a die-receiving jaw having a face on each of said levers, dies detachably attached to each of said jaw faces, a first lever pivotally attached to one of said hand levers, a projection on said lever operative with one of said dies holding said metal in place during said stamping, a second lever connected with said first lever through a toggle joint for forcing said projection against said metal thereby holding said metal in place during the stamping operation.

2. A hand tool for blanking sheet metal comprising a pair of crossed hand levers pivotally attached to each other, a die-receiving jaw having a jaw face on each of said levers, dies detachably attached to said jaws, said dies having openings therein, pins perpendicularly attached to each of said jaw faces co-acting with said openings thereby fixing the position of said dies, said dies attached to said jaw faces by means of screws, an L-shaped lever pivotally attached to one of said hand levers adjacent said jaws, the arm of said jaw extending toward one of said

jaw faces having a projection on the extremity of said L operative with said die for holding said metal in place during the stamping operation, the leg of said L-shaped lever pivotally attached between the extremities thereof to one of said hand levers, a lever arm pivotally attached near but spaced from one end to said L-shaped lever, a link pivotally attached to one of said lever arms, said link pivotally attached to the extremity of the last mentioned hand lever arm adjacent its pivotal point to said L-shaped lever, said link lever and said arm lever thereby forming a toggle joint with said L-shaped lever for operating said L-shaped lever and for clamping the metal to be stamped between the projection on said L-shaped lever and the face of said die with which it is operative therewith.

3. A hand tool for blanking sheet metal comprising a pair of crossed handles pivotally connected, a die receiving jaw on each handle, detachable dies in each jaw, metal clamping means on one of said handles, said clamping means including a metal sheet-engaging arm and a lever connected through a toggle joint, said lever actuating said arm cooperative with one of said dies to hold said sheet in place during stamping.

CELESTINE A. ROYER.
